UNITED STATES PATENT OFFICE.

CHARLES E. ROSS, OF CRAFTON, PENNSYLVANIA.

SPARKING PLUG.

No. 829,545.

Specification of Letters Patent.

Patented Aug. 28, 1906.

Application filed July 9, 1904. Serial No. 215,889.

To all whom it may concern:

Be it known that I, CHARLES E. Ross, a citizen of the United States, residing at Crafton, in the county of Allegheny and State of Pennsylvania, have invented or discovered new and useful Improvements in Sparking Plugs, of which the following is a specification.

In the accompanying drawings, Figure 1 is a longitudinal section of my improved sparking plug. Fig. 2 is a cross-section of the same along the line II II in Fig. 1 looking in the direction of the arrow, while Fig. 3 is an enlarged perspective of my detachable cover.

My invention consists generally in certain novel improvements in electric sparking plugs for use in connection with gas engines or motors. Such plugs are attached to and extend into the cylinder of the engines, and by the spark produced thereby the gas or other power medium is ignited in the cylinder. A great drawback to the proper operation of these devices has been the deposit of soot or other products of combustion on the exposed extremity of the plug, which must be frequently cleansed to produce satisfactory operation. As a preventive of such deposits covers are generally provided which are intended to shield the plug end from such deposits; but while in a measure preventing said deposits the covers themselves have acted as an impediment to the proper cleansing of the plug end, and therefore in a measure increase the fault that they are intended to prevent.

I have devised a detachable cover which not only protects the plug to a large degree from a deposit of objectionable matter, but also may be readily removed for the proper cleansing of the sparking plug. I also so construct my cover that it also acts as a ground-pole for the sparking mechanism, thus simplifying and cheapening the manufacture thereof.

The following is a detailed description of my invention, reference being had to the accompanying drawings, which make part of this specification.

1 1 represent portions of the wall of a cylinder of a gas engine or motor of any type. 2 is an aperture in the wall of said cylinder, preferably annular, reinforced by an integral collar 3, which is internally threaded to engage the threaded end of plug-casing 4. 5 is an externally-squared portion of said plug-

casing by means of which a wrench may be applied for screwing in it place.

6 is a packing of any suitable character, which is compressed between the outer edge of collar 3 and annular shoulder 4^a on casing 6^a 4, thus preventing the escape of gas from the cylinder between the collar and the casing.

7 is a core, usually constructed of porcelain or similar non-conducting material, which is seated in the bore of the hollow 6^a casing 4 and whose inner extremity protrudes slightly from said casing, as shown in Fig. 1. The bore of said casing is enlarged some distance from the inner end, forming an annular shoulder 8, between which and the annular 7^a shoulder 9 on core 7 a packing 10 is compressed, thus preventing the escape of gas from the cylinder through the bore of the casing. The core 7 is retained in place in the casing by means of lock-nut 11, which by 7^a means of its exterior threaded portion 12 engages the interior threaded portion 13 of the casing 4, which also by means of its inner end abuts against shoulder 14 of the core 7.

15 is the electrode-rod, suitably connected 8^a to the source of electric current (not shown) and passing through a central longitudinal aperture in said core 4.

16 is a cap which engages the outer end of core 7 and holds the rod 15 firmly seated in 8^a place and also prevents escape of gas.

The inner extremity of the bore of casing 4 is somewhat enlarged and provided with an annular groove 17.

18 is a cover, preferably stamped out of a 9^a sheet of spring metal, consisting of a circular plate 19 and legs 20 20, said legs being provided with outwardly-extending feet or flanges 21 21.

22 is a boss or projection, preferably struck 9^a up from the metal of the cover, which when the cover is in place on the plug is directly opposite to the sparking end of rod 15, thus forming the ground end of the sparking arc. To place the cover on the plug, the legs 20 20 10^a are sprung together slightly with the fingers and the cover pressed on the end of the plug until the feet 21 21 spring out into and engage the groove 17 in the casing, as shown in Fig. 1, thus firmly securing the cover in place 10^a to protect the extremity of the sparking plug. To remove the cover, all that is required is to spring the legs 20 20 slightly together, so that the feet 21 21 are disengaged from the groove 17, and the cover may be drawn from the 11^a

plug. It is evident, therefore, that the cover not only protects the plug end from a deposit of products of combustion of the gas, but also may readily be removed, so that the plug end 5 may be cleaned without difficulty. The current passing down through rod 15 would jump or spark across to boss 22 and thence pass up through the legs 20 20 to the "ground," which is usually the motor or engine itself, or in case of a stationary engine 10 may be the earth itself.

It is evident that the legs may be made separate from the cover and attached thereto by any convenient means as desired, as by 15 rivets, for example. The boss may also be made separate and attached to the cover and may be connected in any other manner with the ground, as by a wire; but I prefer the construction shown as the most simple and 20 inexpensive.

Many variations of details will occur to the skilled observer, which, however, are within the purview of my invention.

Although for the sake of clearness I have minutely described the accompanying drawings, I do not wish to limit myself thereby, but claim, broadly—

In an electric sparking mechanism, a hollow conducting-casing having an annular groove in the internal periphery thereof, a 30 core of non-conducting material engaging said casing, an electrode-rod passing through said core and a detachable cover of stamped spring metal adapted to protect the exposed end of said core and having integral legs 35 adapted to be sprung into and engage said groove, said cover forming one of the electrodes of said mechanism, substantially as and for the purpose set forth.

Signed at Pittsburg, Pennsylvania, this 6th 40 day of July, 1904.

CHARLES E. ROSS.
